WRENCH

Ole A. Eide, Minneapolis, Minn.

Application November 4, 1939, Serial No. 302,886

7 Claims. (Cl. 81—111)

This invention relates to improvements in wrenches.

The primary object of the invention is to provide a wrench which may be quickly and easily adjusted to the work and by which a powerful and conveniently carried out turning motion may be transmitted to the nut or bolt. A further object is to provide a tool of this kind in a simple and durable form.

These and other more detailed and specific objects will be disclosed in the course of the following specification, reference being had to the accompanying drawing, in which

Fig. 1 is an elevation of my improved wrench, the work engaging jaws being shown in a closed condition.

Fig. 2 is a sectional detail view through an upper part of the wrench shank and associated parts.

Fig. 3 is a similar sectional view but showing a modified gear assembly.

Fig. 4 is a longitudinal, diametrical section through the entire shank and showing the jaws in closed position.

Fig. 5 is a similar view, but showing the jaws in opened position and engaging a nut shown in dotted lines.

Fig. 6 is a cross section along the line 6—6 in Fig. 1.

Fig. 7 is a cross section along the line 7—7 in Fig. 1.

Fig. 8 is a cross section along the line 8—8 in Fig. 1.

Fig. 9 is a detail view of an adjustable link for operating the jaws.

Fig. 10 is an enlarged section along the line 10—10 in Fig. 5.

Referring now with more particularity to the drawing, my improved wrench is shown as taking the general form and shape of a carpenter's brace, having the shank A, U-shaped handle B, and knob C by which the shank may be pressed to the work and rotated by turning said handle B.

In accordance with my invention the shank A is tubular in form providing an axial passage-way 11 and has its lower, or work engaging, end 12 enlarged as shown. Fitted over the other end of the shank is a housing 13 having a passage 14 communicating with the shank and to which housing the handle B is rigidly connected at 15. A gear shaft 16 is journaled at 17 in this housing 13 at right angles to the axis of the shank A, and at one end carries a small gear 18 which meshes with a toothed rack 19 secured at 20 on

the operating rod 21. Said operating rod is slidably but non-rotatably mounted through the passageway 11 in bearings 22 therein and at its lower or outer end carries a head member 23 diametrically slotted to receive a series (four, more or less) of links 24 which are pivotally connected thereto at 25.

Work engaging jaws 26 of elongated flat form are arranged in radially and endwise extended slots 27 in the enlarged end 12 of the shank, and are pivoted intermediate their ends upon pins 28 anchored in said shank. The outer ends of the jaws may thus project endwise from the shank while their inner ends fall at opposite sides of the head member 23, and the jaws may furthermore oscillate about the pins 28 to move radially with respect to the axis of the shank, thereby varying the spacing between their outer ends.

For this purpose the links 24 are pivoted at their outer ends at 29 to the inner ends of the jaws 26, and it will be readily apparent that, by shifting the head member 23 axially, these links, which normally stand in an unfolded or radially extended position (Fig. 4), will be partially folded and will thereby draw the inner ends of the jaws together to spread their work engaging ends, as seen in Fig. 5. This action may of course be brought about by rotation of the shaft 16 to cause the gear 18 to move the rack 19 and so shift the rod 21 within the shank.

Such movement of the gear shaft 16 is carried out by a control mechanism designated generally at 30. In its simplest form this mechanism comprises a knurled collar 31 journaled on handle B and carrying at one extended end (within the housing 13) a gear 32 which meshes with a similar gear 33 on the aforesaid gear shaft 16. Thus, by rotating this collar, the shaft 16 may be turned and the gear 18 will actuate the rack 19 and adjust the jaws either together or apart, depending on the direction in which said collar is turned.

The collar, however, carries a dog or pawl 34 which, under influence of a small spring 35, engages a ratchet member or ratchet teeth 36 on the handle B. This ratchet assembly is designed to normally prevent rotation of the collar 31 in the direction which would cause the jaws 26 to spread apart except when the pawl 34 is disengaged by actual intent. The jaws will thus hold their adjustment once set to the nut, which is indicated at D in Fig. 5, and cannot spread under pressure.

In lieu of the foregoing I may employ the

variation of the operating mechanism shown in Fig. 2, wherein the shaft 16, driven as aforesaid from the collar 31, instead of directly driving the rack 19, is provided with a worm pinion 37 meshing with a small worm gear 38 on a short cross shaft 39. This shaft 39 in turn carries a gear 49 which meshes with the rack 19. The structure thus permits possibly more precise setting of the jaws due to the worm drive employed.

The outer work engaging ends of the jaws 26 are provided with grip members 41 which are pivotally mounted on cross pins 42 through the jaws and may oscillate thereon to always stand parallel with the gripped faces of the nut or work. These grip members have grooves 43 in their inner faces so that, in the case of hexagonal nuts for instance, any two of the jaws may be engaged readily with diametrically opposed corners. The centers of the members are further provided with inwardly turned webs 44 which fit in slots 45 in the jaws to pivotally engage the pins 42 and supplement the mounting of the outer ears 46 and strengthen the assembly.

The links 24 may, if desired, be replaced by adjustable links 24a shown in Fig. 9, and which may be varied in length by turning the threaded collar 47 turnbuckle fashion. The maximum or minimum spacing of the jaws may thus be adjusted, as may be required, while retaining the approximate range of adjustment within such extremes. In order to permit access to the interior of the shank for making such adjustments, or for other reasons, a cover plate 48 is provided over an opening in one side of the shank end 12. This plate is retained in place by a screw 49 and by pilot pins 50 which prevent any possible spreading at the slot 27 adjacent the opening.

It will be apparent from the foregoing that I have provided a wrench which may be readily adjusted to the work, and by which a powerful leverage may be rapidly and easily exerted.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A wrench comprising a tubular shank, a handle extending laterally from the shank, a housing connecting the shank and handle, an operating rod shiftably mounted in the shank, work engaging jaws pivoted on the shank and movable to work engaging positions by shifting movement of the rod, a gear train rotatably mounted in the housing, a rack on the operating rod engaged by one gear of the gear train, a collar rotatably mounted on the handle, and a gear on said collar operatively arranged for actuating said gear train.

2. A wrench comprising a tubular shank, a handle extending laterally from the shank, a housing connecting the shank and handle, an operating rod shiftably mounted in the shank, work engaging jaws pivoted on the shank and movable to work engaging positions by shifting movement of the rod, a gear train rotatably mounted in the housing, a rack on the operating rod engaged by one gear of the gear train, a

collar rotatably mounted on the handle, a gear on said collar operatively arranged for actuating said gear train, and ratchet means for normally locking the collar against movement in one direction.

3. A wrench comprising a tubular shank, a handle extending laterally from the shank, a housing connecting the shank and handle, an operating rod shiftably mounted in the shank, work engaging jaws pivoted on the shank and movable to work engaging positions by shifting movement of the rod, a collar rotatably mounted on the handle adjacent the housing, a gear on said collar, a worm and worm gear actuated by rotation of said collar, a toothed rack on said operating rod, and a gear driven by said worm and worm gear and meshed with said rack for shifting the operating rod and adjusting the jaws.

4. A wrench comprising a tubular shank, a handle for turning the same, the said shank having an enlarged, partially hollow and slotted end, jaws pivotally mounted in the slots, an operating rod shiftably mounted between the jaws, means for shifting the rod, links pivotally connected between the rod and jaws and adapted to adjust the latter in response to shifting movement of the rod, the said links being of adjustable length, and the said hollow end of the shank having a lateral opening affording access to the links for adjusting the same.

5. A wrench comprising a tubular shank, a handle for turning the same, the said shank having an enlarged, partially hollow end, jaws pivotally mounted in the said hollow end, an operating rod shiftably mounted between the jaws, means for shifting the rod, links pivotally connected between the rod and jaws and adapted to adjust the latter in response to shifting movement of the rod, the said links being of adjustable length, and a removable cover plate on the enlarged end of the shank and adapted when removed to expose the links and connections within said shank end for adjustment purposes.

6. In a wrench, a shank, a handle extending laterally from the shank, jaws movably mounted in the shank, a rack member for moving the jaws, a collar journaled on the handle, a shaft journaled on an axis parallel with the axis of rotation of the collar, a gear on the shaft for engaging and shifting the rack, a gear secured to the collar for rotation thereby, and another gear on the shaft meshing with the gear on the collar whereby said shaft may be rotated by the collar.

7. In a wrench, a shank, a handle extending from the shank for turning the same, a collar rotatably mounted adjacent the junction of the handle and shank, jaws movably mounted on the shank, means including a rack for moving the jaws, a shaft journaled alongside the rack and a gear on said shaft for engaging the rack, a worm shaft journaled adjacent the collar, a worm on the worm shaft, a worm gear on the first mentioned shaft and meshing with the said worm, a gear on the collar, and a gear on the worm shaft meshing with the said gear on the collar whereby rotation of the collar will rotate the shafts and move the rack and jaws.
